PORTABLE ROLL PICKER

Edward E. Hart, Springfield, Ohio, assignor to Globe Industries, Inc., Dayton, Ohio, a corporation of Ohio
Continuation of application Ser. No. 315,630, Oct. 11, 1963. This application Oct. 31, 1966, Ser. No. 591,030
2 Claims. (Cl. 310—51)

This application is a continuation of Ser. No. 315,630, filed Oct. 11, 1963 and is now abandoned.

This invention relates to a portable rotary tool which includes a rotating shaft or spindle for removing very loosely packed accumulations of lint from textile machinery.

Devices of the type with which the invention is concerned are referred to as "roll pickers" and generally consist of some motive power which drives a long, smooth, tapered spindle or shaft of small diameter rotating at a relatively high speed, e.g., 12,000—15,000 r.p.m. As is well-known, lint, if allowed to accumulate on rotating members of textile machinery, tends to pack very tightly and eventually will force its way inside bearing journals and other critical areas, thus causing damage to the machine or ruining spools of thread. The roll picker operates in such manner that the rotating spindle is surrounded by a boundary layer of air which when placed adjacent the lint carrying rotating member of the textile machine will serve to catch the light outer fibers of the accumulated blanket of lint. Since the blanket of lint on the textile machinery roll is composed of fibers alighting at random on the machine, it is essentially interwoven throughout, and the outer fibers, once caught up by the rotating spindle, will serve to remove the entire blanket from the section of the machine. The lint, thus removed from the machine, is then discarded and the roll picker is again made available for continued operation.

Such devices as above described have customarily been operated from compressed air sources, with the attendant disadvantage that long trailing air hoses must be attached to the device as the operator progresses down the line of textile machines. Obviously, such tools when air driven have the disadvantage of presenting a safety hazard due to the trailing hoses, and also of being somewhat cumbersome in that the operator must manipulate a tool having attached thereto a relatively heavy hose.

It is therefore one object of the invention to provide a roll picker capable of portable operation, and which has all of the advantages of air driven tools.

It has been found, in the use of roll pickers, that the operator will apply pressure to the tool as it is applied towards the rotating part of the textile machinery, instead of merely bringing it closely adjacent thereto. In the case of air driven tools, generally there is sufficient air pressure available to still continuously rotate the spindle at the proper speed so that the device operates. However, in the case of portable devices where the power supply is generally limited, should pressure be applied on the roll picker and blade, the motor will generally lose speed and the device will cease to operate. Usually, when the motor is thus overloaded and slowed down, it will drain the power source and perhaps damage it.

After extended use of roll picker devices, it has been observed that the spindles or blades will become permanently bent out of shape, and upon operation of the device, unwanted vibration or blade whipping will occur. However, as indicated above, in the case of air driven units there is generally sufficient power available to drive the unit through the whipping or vibrating condition, or alternatively, the vibration can be damped out by wiping the blade with the hand. In the case of portable devices, generally the power supply is so limited that insufficient power is available to drive the spindle through its vibrat-

2

ing condition. In the case where an electric motor is mounted in a portable device to rotate the blade, I have found that the first mode resonant frequency of blades is close to the no load motor speed, and thus the slightest eccentricity of the blade tip will cause the blade to begin vibrating as the motor comes up to speed. As the motor approaches maximum speed, the blade goes into resonance and the amplitude is great enough so that the induced load will not permit the motor to pull through this speed, hence maintaining the whipping condition. As indicated above, motor current also becomes excessive, thus causing either rapid deterioration of the power source or premature burning out of the brushes. It is therefore a further object of the invention to provide a portable roll picker providing means whereby eccentricity of the blade tip will not cause destruction of the motor or its power supply.

I have found in the case of portable battery operated roll pickers that the battery will excessively discharge unless some type of relay device is incorporated into the circuit which will open the circuit when the battery potential drops below a given value, and close the circuit when it rises above a slightly higher value. The problem with such relay devices is that there is no commercially available relay small enough to conveniently be employed in a hand-carried roll picker. I have further determined that the pull-in to drop-out ratio of relays commercially available is so high that such relays cannot operate over a small voltage range comprising only a slight differential between drop-out voltage and pull-in voltage. It is therefore a still further object of the invention to provide a voltage protection circuit in a roll picker for a portable battery, enabling the preservation of long battery life.

These and further objects of the invention will become more readily apparent upon a reading of the description following hereinafter, and upon an examination of the drawings, in which:

FIG. 1 represents a cross-sectional view through the device of the invention;

FIG. 2 represents one voltage control circuit for the roll picker;

FIG. 3 represents a modified control circuit similar to that of FIG. 2; and

FIG. 4 is a schematic illustrating a preferred voltage control circuit for the roll picker of the invention.

As indicated above, the problem of unwanted vibration or whipping of the blade in a roll picker becomes acute when it is attempted to provide a portable electric motor driven battery operated device. The primary factor causing this problem is that due to the high speed motors which must necessarily be employed, the first mode resonant frequency of relatively short blades is close to the no load motor speed. The slightest eccentricity of the blade tip (i.e., as would be caused by ordinary handling of the device) causes the blade to begin vibrating as the motor comes up to speed. As the motor approaches maximum speed, the blade goes into resonance and the amplitude becomes so great that the induced load will not allow the motor to pull through this speed, so the whipping condition is sustained. During this condition, the motor will draw excessive current. I have found that by placing O-rings around the motor frame and mounting it to the case through an elastic mounting, while otherwise permitting freedom of motion within the case, serves to isolate the motor from the case or handle. This allows the motor to move when the blade starts going into resonance, thus damping it out sufficiently for the motor to continue its speed build-up and pull through the critical speed.

Referring now to FIG. 1, it is seen that the motor 4 is mounted within the case 2 of a roll picker 1. The motor 4 is coupled to a blade or spindle 3 which is shown as

being tapered. The coupling between the motor and the spindle is accomplished by a connector member 6 which is mounted on the motor shaft 5 as by the set screw 7, and to the spindle 3 as by the set screw 8. The motor 4 is comprised of a rotating armature 42 and the stator 28, and may be of the permanent magnet or wound field D.C. type. The armature 42 is provided with a commutator and brushes 24 and 26 as will be understood by those skilled in the art.

Power to the motor 4 is provided by the electrical cord 14 which is mounted through the rear end of the case 2 through a grommet 10 to the brushes 24 and 26, respectively. The lead 20 is connected to a push-button switch 18 which also has connected to it the lead 16 of the supply line 14.

The motor 4 is mounted within the case 2 by a pair of O-rings 30 and 32, and by the screw 34 which is threaded into the case of the motor at 40. The screw 34 is mounted within a sleeve 36 of preferably stiff material, which sleeve in turn is surrounded by a sleeve 38 of elastic material. Sufficient clearance is provided between the motor 4 and the case 2 so that upon operation of the device and the commencement of any vibrations, the elastic mounting of the motor within the case will quickly dampen out such unwanted vibrations.

As indicated above, it is desirable that as the portable battery loses its power, there comes a point where power from the power supply be disrupted to the motor. This is brought about by the provision of a control circuit located within the space 9 of the case 2. This control circuit is so designed that when the power available from the power supply drops below a predesignated point, the circuit is opened to the motor, and should the battery recover sufficiently to a higher level, then the circuit will again be closed to provide power to the motor. The happening of this on/off cycle will serve as a warning signal to the operator to replace and/or recharge the battery immediately. One such control circuit is indicated in FIGURE 2 wherein the battery 44 supplies power to the motor armature 42 through the lines 20 and 22. The switch 58 is a push-button switch similar to the switch 18 of FIG. 1. When the switch 58 is closed, then current will flow from the battery 44 through lines 46 and 56 through coil 52. The zener diode 54 is so chosen that a minimum voltage must be available from the battery 44 before current will flow through the circuit (i. e., the zener level). When current flows through coil 52, sufficient flux is created to close the reed switch 50, thus permitting current to flow through lines 22 and 20 to the motor armature 42. As the battery 44 discharges, then the current will fall below the zener level of diode 54, thus blocking flow through lines 46 and 56. When current ceases to flow through lines 46 and 56, then coil 52 will no longer be enabled to hold the reed 50 closed. When this occurs, then the reed 50 will open to remove power from the motor armature 42.

Although under ordinary circumstances the circuit of FIG. 2 will prove to be sufficient, it has been found that with particular power supplies having high recovery rates, and with high speed motors of custom design, the battery 44 will quickly recover to raise the voltage level above the zener level and thus reactivate the switch 48. This action will be immediately followed by a high surge of current of the motor when re-energized to immediately again lower the potential below the operating range of the zener diode 54 and the circuit is again caused to open. This action cycles at a very high rate which quickly pits the reeds of switch 48 and latches them closed. When the reeds are struck, the push-button switch 58 could be released, but would no longer control the motor. In order to overcome such disadvantage the arrangement of FIG. 3 may be employed. In this circuit the switch 58 is placed in series with the armature 42 leads 20 and 22, so that regardless of what happens to the reed 50 of the switch 48, the power to the motor armature 42 may still be dis-

connected by releasing the push-button switch 58. In this circuit when the push-button switch 58 is initially depressed and the power supply 44 is of a potential which exceeds the zener level of zener diode 80, then current will flow through line 82, through zener diode 80 and resistance 78 to create the proper bias on the base 76 of transistor 70 to turn the transistor on. When the transistor 70 is turned on, then current will be enabled to flow through line 22 and through the emitter to collector path 72-74 of transistor 70. It is noted that instantaneously prior to the time that the emitter collector path of transistor 70 is closed, current will flow through the base collector path 74, 76 of transistor 70 to pass current through coil 52 and close the switch 48 by drawing the reed 50 closed. This instantaneous delay prevents any surge current from damaging the transistor 70. Also, since only small amounts of power are required to turn transistor 70 on, the cost of the several components may be reduced by employing lower cost zener diodes.

Even though the circuit of FIG. 3 may be employed to remove the possibility of current continuing to flow through the armature 42 when the push button 58 is released, it is still found that should the operator not realize what is occurring (usually the cycling of the reeds 50 will cause an audible buzzing in the instrument), then the operator will continue to depress push button 58 and cause the motor failure problem indicated above. To avoid such shortcomings, the circuit of FIG. 4 is preferably employed. In this preferred embodiment the push-button switch 58 is again employed in series with the motor armature 42 via leads 20 and 22 from the battery 44. However, a pair of transistors 102 and 130 are employed in the following manner. With both transistors turned off, the push button 58 is depressed, and in the event the power supply 44 is of a potential which exceeds the zener level of the zener diode 110, then current will flow through the base emitter path 100-108 of the transistor 102 to turn the transistor 102 on. When transistor 102 is turned on then current will flow through its emitter collector path 104-105, through line 118 and through coil 50. When current passes through coil 50 the reed 52 is drawn to close the switch 48 and permit current to flow to the armature 42. A capacitor 122 is employed in a shunt path 120 to minimize arcing of the reed 52. As the power supply 44 discharges, the potential in line 112 will fall below the zener level of zener diode 110, thus removing the bias on the base 108 of transistor 102 and turn it off. When transistor 102 is turned off, current will no longer flow in line 118 so that the switch 48 will be opened to remove power from the motor armature 42. In order to prevent the cycling of the reed 52 as discussed above when the power supply 44 momentarily recovers, a positive latch out action is accomplished by the provision of the second transistor 130. As long as switch 58 remains closed, although switch 48 is opened by the action just described to remove power from the armature 42, current will still flow from the battery 44 through the emitter collector path 134-136 of transistor 130. The transistor 130 ordinarily is turned off when the transistor 102 is turned on because of the values of resistances 116, 114 and 126. For example, the resistance 114 may be five or six times that of resistance 116, whereas the resistance 126 may be five or six times that of 114, and consequently 30 times that of resistance 116. With such a selection of components, when transistor 102 is turned on current will be prevented from flowing past resistance 126 through lead 118. However, once transistor 102 is turned off, then the capacitor 142 which has previously been charged up will be permitted to discharge, thus imposing a bias upon the base 132 of transistor 130 to turn it on. Current will thereafter flow from power supply 44 through the closed switch 58, the emitter collector path 134-136 of transistor 130, resistance 116 back to the negative terminal of battery 44. As long as switch 58 remains depressed, the transistor stays on and

it is only turned off when the switch 58 is opened to remove the bias on base 132 of transistor 130. Thereafter, when switch 58 is depressed, and in the event the power supply 44 does not provide a potential which exceeds the zener level 110, no current will flow in either circuit of transistor 130 or 102. Upon the substitution of a properly charged power supply 44, when switch 58 is activated then the proper potential is available to exceed the zener level of zener diode 110 and transistor 102 is turned on as indicated above. In this manner pitting of the reed 52 of the switch 48 is avoided regardless of the inattention of the operator.

Although various specific embodiments have been described above, it will be readily understood by those skilled in the art that various rearrangements of parts and modifications of parts may be accomplished without departing from the spirit and scope of the invention as defined in the appended claims.

What I claim is:

1. A portable battery operated roll picker comprising, in combination:
  - a hollow elongated housing open on one end thereof adapted to be hand held,
  - a high speed electric motor operating at a speed of at least 10,000 r.p.m. mounted coaxially at the open end of said housing, and having an output shaft protruding from said open end of said housing,
  - an elongated spindle member mounted to the motor out-

put shaft and extending coaxially with said housing, said spindle member having a first mode resonant frequency substantially within the range of the no load motor speed and when driven above said resonant frequency serves to strip lint from textile machinery rolls, and

elastic vibrating damping mounting means encircling said motor for holding and retaining said motor-spindle assembly with respect to said housing in spaced relationship therefrom to provide the sole support therefor and permitting restricted relative movement of the motor with respect to the housing at or near the resonant frequency of the spindle member while preventing physical contact of the motor with said housing and damping out motor and spindle vibration sufficiently to enable the motor to run through the critical speed.

2. The portable battery operated roll picker of claim 1 wherein said elastic vibration damping mounting means comprises a member affixed to said motor and protruding through said opening in said housing, said protruding member being surrounded by a yieldable element extending between said housing and said member.
